CLAIM

The ornamental design for a canopy, as shown and described.

DESCRIPTION

FIG. 1 is an isometric view of the canopy of our new design; FIG. 2 is a front elevational view thereof;

FIG. 3 is a rear elevational view thereof;

FIG. 4 is a right side elevational view thereof, the left side elevational view being a mirror image thereof;

FIG. 5 is a top plan view thereof; and,

FIG. 6 is a bottom plan view thereof.

The broken line showing in the drawing figures is for illustrative purposes only and form no part of the claimed design.
